United States Patent Office

Des. 215,428
Patented Sept. 30, 1969

215,428

STOOL

John W. Tapert, Detroit, Mich., assignor to Design Workshop, Inc., Detroit, Mich., a corporation of Michigan

Filed Feb. 26, 1968, Ser. No. 10,713

Term of patent 14 years

Int. Cl. D6—01

U.S. Cl. D15—8

FIGURE 1 is a top plan view of the stool, showing my new design.

FIGURE 2 is a side elevational view of the stool shown in FIGURE 1.

FIGURE 3 is a side elevational view thereof taken 45° from the view in FIGURE 2.

FIGURE 4 is a bottom plan view.

FIGURE 5 is a perspective view.

I claim:

The ornamental design for a stool, substantially as shown.
